CLAIM

The ornamental design for a connector frame, as shown and described.

DESCRIPTION

FIG. 1 is a front elevational view of a connector frame;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a reduced front, top and right side perspective view thereof;

FIG. 8 is a reduced front, bottom and left side perspective view thereof; and,

FIG. 9 is an even further reduced front, top and right side exploded perspective view.

The elements shown in broken line are for illustrative purposes only and form no part of the claimed design.
